The ornamental design of an electric toothbrush handle, as shown and described.

DESCRIPTION

FIG. 1 is a perspective view showing the electric toothbrush handle of my design;

FIG. 2 is a front elevational view thereof, the rear elevational view being identical thereto;

FIG. 3 is a right side elevational view thereof, the left side being identical thereto;

FIG. 4 is a fragmentary sectional view taken along line 4—4 in FIG. 6;

FIG. 5 is a top view thereof;

FIG. 6 is a bottom view thereof; and,

FIG. 7 is a view like FIG. 2 but showing in broken lines a removable toothbrush mounted thereon.

The broken line showing of the toothbrush in FIG. 7 is for environmental purposes only and forms no part of the claimed design.
